Inventor:

A. C. Lanning

UNITED STATES PATENT OFFICE.

A. C. LANING, OF WILKES-BARRE, PENNSYLVANIA.

PUMP.

Specification of Letters Patent No. 23,690, dated April 19, 1859.

To all whom it may concern:

Be it known that I, A. C. LANING, of Wilkes-Barre, in the county of Luzerne and State of Pennsylvania, have invented a new and useful Improvement in Reciprocating Pumps; and I do hereby declare that the following is a full, clear, and exact description of the same, reference being had to the annexed drawings, making a part of this specification, in which—

Figure 1, is a longitudinal section of my invention taken in the line x, x , Fig. 2. Fig. 2, is a side view of the same with the valve chamber bisected longitudinally as indicated by the line y, y , Fig. 1.

Similar letters of reference indicate corresponding parts in the two figures.

This invention relates to an improvement in reciprocating pumps and is designed to render the same capable of being used in an inclined or horizontal position equally as well as in a vertical one.

The invention is more especially designed for mining and similar purposes, where pumps are frequently necessarily inclined and often placed in a horizontal position.

The ordinary reciprocating pump is admitted to be preferable, when placed in an upright position, but cannot be advantageously used in an inclined or horizontal position, in consequence of the wear produced by the plunger bearing on and working against the side of the cylinder, the wear soon causing the pump to work very imperfectly. By my invention this difficulty is obviated.

To enable those skilled in the art to fully understand and construct my invention I will proceed to describe it.

40 A, represents a stationary pipe or tube which has a valve, chamber B, communicating with it at one end. This chamber B, is provided with two valves a , and b , the valve

a , opening inward and the valve b , opening outward.

45 C, is a cylinder which is fitted on the pipe or tube A, and is allowed to slide freely thereon. This cylinder C, is closed at its outer end and has a tug iron c, attached for the purpose of connecting a rod to operate 50 the cylinder. To the inner end of the cylinder a stuffing box D, is attached, for the purpose of allowing the cylinder to work water tight over the pipe or tube A. The cylinder C, has projecting plates or bars d, at its 55 sides, said plates or bars being fitted on guides e, e, which are attached to uprights f, said uprights being secured to a plate F, to which the pipe or tube A, is also secured.

From the above description it will be seen, 60 that by giving the cylinder C, a reciprocating motion the water will as the cylinder C, moves outward in the direction of arrow 1, be drawn through valve a , and as the cylinder moves in the opposite direction, indicated by arrow 2, the water will be forced 65 through the valve b . It will be seen that the pump may be placed in an inclined position and in a horizontal or vertical position and work equally well in either case. 70 The ordinary reciprocating pump cannot be thus used as the weight of the piston when the pump is inclined soon produces wear and materially affects its operation.

Having thus described my invention what 75 I claim as new and desire to secure by Letters Patent is—

The stationary pipe or tube A, valve chamber B, and reciprocating cylinder C, combined and arranged substantially as and 80 for the purpose set forth.

A. C. LANING.
